(57) **CLAIM**

The ornamental design for a compressible lantern, as shown and described.

DESCRIPTION

FIG. 1 is a perspective view of a compressible lantern of our design.

FIG. 2 is a front view of the compressible lantern of FIG. 1.

FIG. 3 is a rear view of the compressible lantern of FIG. 1.

FIG. 4 is a side view of the compressible lantern of FIG. 1.

FIG. 5 is a second side view of the compressible lantern of FIG. 1.

FIG. 6 is a top view of the compressible lantern of FIG. 1.

FIG. 7 is a bottom view of the compressible lantern of FIG. 1.

FIG. 8 is a perspective view of the compressible lantern of FIG. 1 in a compressed configuration.

FIG. 9 is a front view of the compressible lantern of FIG. 1 in a compressed configuration.

FIG. 10 is a perspective view of second embodiment of a compressible lantern of our design.

FIG. 11 is a front view of the compressible lantern of FIG. 10.

FIG. 12 is a rear of the compressible lantern of FIG. 10.

FIG. 13 is a side view of the compressible lantern of FIG. 10.

FIG. 14 is a second side view of the compressible lantern of FIG. 10.

FIG. 15 is a top view of the compressible lantern of FIG. 10.

FIG. 16 is a bottom view of the compressible lantern of FIG. 10.

FIG. 17 is a perspective view of the compressible lantern of FIG. 10 in a compressed configuration; and,

FIG. 18 is a front view of the compressible lantern of FIG. 10 in a compressed configuration.

The broken line showing represents portions of the compressible lantern not claimed and forms no part of the claimed design.

1 Claim, 12 Drawing Sheets
